UNITED STATES PATENT OFFICE.

JOHN A. DAVISON, OF VANCOUVER, BRITISH COLUMBIA, CANADA, ASSIGNOR OF ONE-HALF TO IRA M. COBE AND STUART C. PRATT, DOING BUSINESS AS COBE & PRATT, OF NEW YORK, N. Y.

SHOE-POLISHING CLOTH.

Application filed January 8, 1925. Serial No. 1,318.

To all whom it may concern:

Be it known that I, JOHN A. DAVISON, of 1056 Alberni Street, Vancouver, British Columbia, in the Dominion of Canada, a subject of the King of Great Britain, have invented certain new and useful Improvements in Shoe-Polishing Cloths; and I do hereby declare the following to be a full, clear, and exact description of the invention, such as will enable others skilled in the art to which it appertains to make and use the same.

My invention relates to improvements in shoe polishing cloths.

The object of my invention is to provide a shoe polishing cloth in which each end of the cloth is provided with means whereby the cloth may be gripped while rubbing and polishing the shoes, as is well understood by those skilled in the art, and so constructed that the same can be rolled up and held within a cover so that the cloth can be carried in a grip or in the pocket and will not soil the hands or anything that it comes in contact with.

Another object of my invention is to provide a simple, cheap and effective cloth of this character which forms a compact package when rolled and having certain details of structure and combination of parts herein-after more fully set forth.

In the accompanying drawings:—

Figure 1 is a perspective view of my improved shoe polishing cloth rolled within the cover.

Figure 2 is a perspective view of the cloth in the unrolled position showing the felt side of the cloth.

Figure 3 is a longitudinal vertical sectional view of Figure 2.

Referring now to the drawings, 1 represents a piece of cloth, which as is well understood by those skilled in the art, is provided on one face with a felt like finish 2, which is for the purpose of causing a more perfect polish to the shoe. One end of the cloth 1 has its ends turned over and stitched

as indicated at 3, forming the hem 4 into which the wooden strip or a rod 5 is inserted to form a handle for gripping the polishing cloth. The opposite end of the cloth is turned over as indicated at 6, and stitched to the covering 7 by the stitching 8. The point of attachment of the end of the polishing cloth is mid-way between the ends of the covering 7, whereby the portion 9 of the covering may form a gripping surface for the hand when used for polishing shoes. This portion 9 is provided with a snap eye 10, adapted to snap over the flexible button member 11, carried by the opposite face of the end 12 of the cover.

By this structure it will be seen that I have provided an improved polishing cloth in which the cloth can be readily rolled up and the cover wrapped around and held in position by the snaps 10 and 11. The cloth is rolled upon the strip 5 so that a very neat compact package is obtained and in which the polish stained cloth is wholly covered by the covering 7, and held in its rolled condition thereby.

Having thus fully described my invention what I claim is:—

1. A polisher of the character described comprising an elongated polishing cloth, having a hem at one end, a strip enclosed in the hem for forming a handle, and the opposite end of the cloth being attached to the intermediate portion of the covering, said covering being adapted to completely enclose the cloth when rolled on the handle.

2. A polisher of the character described comprising an elongated polishing cloth having a strip attached to one end, and upon which the cloth may be rolled, the opposite end of the cloth being attached to a flexible covering intermediate its ends, and the flexible covering having snaps adapted to hold the covering around the roll.

In testimony whereof, I have signed this specification.

J. A. DAVISON.
